COMBINATION HEATING AND COOKING
STOVE

Lawrence A. Althoff, Chicago, Ill.

Application February 1, 1935, Serial No. 4,565

3 Claims. (Cl. 126—4)

This invention relates to a combination heating and cooking stove and may be employed in connection with a single unit as illustrated herein or in combination with a cooking range or other form of stove.

A primary object of the invention is to provide a heater and cooking stove which is compactly and attractively constructed, and which may be operated with efficiency and with a modicum of effort. Other specific objects and advantages will appear as the specification proceeds.

The invention is illustrated, in a preferred embodiment, by the accompanying drawings, in which—

15 Figure 1 is a front view in elevation of a stove construction embodying my invention, the top cover and front door being shown in open position; Fig. 2, a side view in elevation, the front door being closed and top cover being partially raised; Fig. 3, a top plan view, the top cover being partially broken away; Fig. 4, a sectional view, the section being taken as indicated at line 4 of Fig. 2; Fig. 5, a bottom plan detail view; and Fig. 6, a sectional view, the section being taken 25 as indicated at line 6 of Fig. 1; and Fig. 7, a sectional detail view of a modified form of the invention.

In the illustration given, I provide an angle iron base 10 supported upon legs 11. Clamped between the legs 11 and the angle iron base 10 are the lower turned edges of metal side walls 12. The rear wall 13 rests upon the base 10 as shown more clearly in Fig. 6, and is provided with an aperture 14 through which the outlet flue 35 15 extends.

The front of the range is provided with side frame pieces 16 and a door 17 is hinged to the side frame piece 16. It will be observed that the door does not extend to the top of the outer frame 40 casing, but terminates at a point substantially flush with the inner stove top. A top cover member 18, hingedly connected at its rear end, is provided at its front end with a depending wall 19 adapted to meet substantially the top of the door 17. The top cover 18 is preferably provided with air outlet openings 20, and the side walls 12 are also provided near their top with air openings 21.

The inner stove is preferably a unitary structure resting upon the angle iron frame 10. The structure may be of cast iron or any other suitable construction. As shown more clearly in Figs. 4 and 6, the bottom wall 22 is provided at its forward end with a depending flange 23 which rests upon the angle iron 10. The rear end of

the bottom wall 22 is secured to the rear wall 13 by flanges 24. The bottom wall is provided near its forward end with a depending box 25 having air openings 26 therein controlled by the perforated plate 27 which is slidably secured to box 25 by screws 28 which engage slots 29 in plate 27. A pivoted bar 30 is provided with a handle 31 extending to the front of the stove and providing a means for controlling the inlet of air.

The bottom plate 22 is supported above the base 10 and the bottom wall of box 25 so as to provide an air space therebetween. The plate is provided with air openings 33 just above the box 25 to permit air to pass from the box upwardly along the sides 34 of the inner stove. Spaced inside of the walls 34 are air inlet walls 35 which, together with walls 34, provide an air space directly above the slots 33. An ash hopper or bin 36 is slidably supported inside of walls 35 and upon the plate 22. Secured to the side walls 34 directly above the walls 35 are downwardly and inwardly inclined baffles or guides 37. The baffles 37 are spaced sufficiently above the walls 35 to permit air to pass under the inner 25 free ends of the baffles and then upwardly through the grate.

The grate 38 of well known construction is supported above baffles 37, and a fire-box 39 also of well known construction is supported upon members 40 which are secured to the walls 34 and which also form a portion of the grate. In view of the well known construction of the fire-box and grate, a detailed description will not be given.

The rear top wall of the inner stove is adapted to serve as a cooking top and is provided with a removable circular top 41. The forward end of the stove top is in the form of a lift door 42 which is hinged at its rear side to an intermediate 40 portion 43 of the stove top. The forward end of door 42 engages a front beam or bar 44 which serves as a rest for the coal scuttle when the door 42 is raised. The fire-box 39 is also provided with the usual door 45 closing the front side of 45 the fire-box.

In order to support the top cover 18, I provide a latch member 46 which is provided with notches adapted to engage the lug 47 carried by the outer stove frame, as shown more clearly in Fig. 3.

In the operation of the stove, the required amount of air may be admitted through the bottom air box 25 by sliding the damper plate 27 to the desired position. The air enters, as shown more clearly in Fig. 4, through the apertures 26 55

and then through slots 33 in plate 32. The air passes upwardly through passages formed by walls 34 and 35 and then inwardly under baffles 37. The prewarmed air then passes through the bottom of grate 38 and directly into firebox 39. If desired, openings may be provided in the lower portion of side walls 34 adjacent the walls 35 for allowing the admission of air to the inner stove, but I prefer not to have the air enter at a point thereabove. The inwardly turned baffles 37 prevent the air passages from being clogged with ashes and at the same time, direct the ashes into the hopper 36. The air outside of the inner stove enters at the bottom of the range and passes along the sides 12 in contact with the heated walls 34 of the inner stove. The air then passes out of openings 20 at the top of the range and side openings 21.

When the top cover 18 is in lowered position 20 and the front door 17 is closed, the inner stove is completely hidden from view and the entire structure functions efficiently as a heating stove. When the cover 18 is raised, the top of the inner stove is exposed and the cooking top may be used. 25 When it is desired to replenish the coal supply, the front top 42 may be raised to a position slightly tilting rearwardly, at which position it maintains itself, and a scuttle of coal may be raised so that the neck thereof rests upon beam 30 44. In this manner, coal may be readily and quietly fed into the fire-box. With the construction illustrated, the top cover of the range is supported at a suitable distance above the heated top of the stove so as to prevent injury 35 thereto from the heat, while at the same time, the stove 42 is rendered readily accessible for replenishing the coal supply. It will be observed that the depending wall 19 of the top cover 18 terminates substantially in line with the cross beam 44.

40 In the modification shown in Fig. 7, the cover 48 is divided intermediate its length and provided with a hinge 49. The forward end of the cover 48 is equipped with a perforated lug 50 adapted to receive one end of a hook 51. The other end of the hook engages a metal loop 52 secured to the lift-cover 53. With this construction, the cover 48 and lift-top 53 may be lifted simultaneously with one hand when it is desired

to introduce coal into the fire-box below the lift-top 53.

While in the foregoing illustrated description, I have set forth a specific preferred structure, it will be understood that considerable variation 5 may be made in the details of construction without departing from the spirit of my invention. The foregoing detailed description has been given for clearness of understanding only, and no unnecessary limitations should be understood therefrom, but the appended claims should be construed as broadly as permissible, in view of the prior art.

I claim:

1. In a structure of the character set forth, an 15 inner stove, a sheath-casing extending about the sides and above the top of said stove, said sheath-casing being open at its bottom and spaced from the sides of said stove, a front casing wall ex- 20 tends up to a point adjacent the top of said stove, a cover hingedly connected at its rear end to said casing, and a front wall portion attached to said cover and depending perpendicularly from the front end thereof.

2. In a structure of the character set forth, an 25 inner stove, a sheath-casing extending about the sides and above the top of said stove, said sheath-casing containing an opening in its bottom and being spaced from the sides of said stove, a front casing wall extending up to a point adjacent the 30 top of said stove, a cover flush with the top of said sheath-casing and hingedly connected thereto, and a front wall portion attached to said cover and depending from the front end thereof, the sides of said front wall portion being 35 flush with the sides of said cover.

3. In a structure set forth, a base supported by legs, an inner stove structure supported on said base, and an outer casing about said inner stove structure, said casing having a pivoted 40 cover extending at a space distance above the top of said inner stove structure, said cover having a depending front wall with its lower edge substantially aligned with the top of said inner stove structure, said stove structure and outer 45 casing providing an uninterrupted air passage from the bottom to the top of said casing.

LAWRENCE A. ALTHOFF.
